SEQUENCED PHASE PANELBOARD

John A. Herrmann and Elwood T. Platz, Grosse Pointe Farms, Mich., assignors to I-T-E Circuit Breaker Company, Philadelphia, Pa., a corporation of Pennsylvania

Filed June 5, 1963, Ser. No. 285,680

11 Claims. (Cl. 317—119)

This invention relates to panelboards in general and more particularly to a multi-phase panelboard for light industrial applications.

The Farnsworth et al. pending application Serial No. 806,959, filed April 16, 1959, now abandoned, discloses a panelboard for mounting circuit breakers of the type illustrated in the R. W. Thomas, U.S. Patent No. 2,938,983, issued May 31, 1960, entitled Circuit Breaker Latch. The circuit breaker illustrated in the aforesaid patent is provided with line and load terminals which project from the same side of the circuit breaker housing with this side of the housing in front of the panelboard mounting plate. Mounting hooks are provided for the circuit breaker with these hooks extending from a housing wall which is opposite the wall containing the terminals. Heretofore panelboards for mounting such circuit breakers consisted of a central mounting rib with single bus bars parallel to the rib on opposite sides thereof as illustrated in the aforesaid copending application 806,959.

Heretofore, no practical arrangement has been proposed for providing more than one bus bar on the same side of the mounting rib. Accordingly, panelboards for this type of circuit breaker were limited to three wire single phase units. Because of this the application of the circuit breakers was limited. That is, in many installations three phase electrical energy is present and no practical three phase panelboard had been provided by the prior art for circuit breakers of this type.

The instant invention provides a novel and practical panelboard construction for the utilization of circuit breakers in which both the line and load terminals are mounted to the housing wall which is opposite the wall carrying the mechanical mounting means for the circuit breaker. Briefly, the device of the instant invention provides a U-shaped insulator positioned with a circuit breaker mounting rib midway between the arms of the U and extending parallel thereto. Three U-shaped bus bars are substantially enclosed by the insulator and are so constructed that circuit breaker connecting portions thereof extend outside the confines of the insulator.

The circuit breaker connecting portions of the bus bars are arranged in rows extending parallel to the mounting rib with these connecting portions being positioned in a single plane at the forward surface of the insulator. The bus bars are so constructed that the circuit breaker connecting portions are sequenced. That is, a connecting portion of one bus bar is positioned between a connecting portion of a second bus bar and a connecting portion of the third bus bar. This is in compliance with requirements of electrical codes and also facilitates the mounting of multi-phase circuit breakers of the type illustrated in the pending application, Serial No. 285,681, filed June 5, 1963, entitled Multi-Phase Circuit Breaker, with E. T. Platz as inventor and assigned to the assignee of the instant invention.

Accordingly, a primary object of this invention is to provide a novel construction for a three phase panelboard to receive circuit breakers whose contacts are mounted to a housing wall which is opposite the housing wall having the mechanical mounting means for the circuit breaker.

Another object is to provide a panelboard of this type which is of substantially the same width as three wire single phase panelboards for circuit breakers of this type.

2

Still another object is to provide a three phase panelboard of this type in which the phasing is sequenced.

A further object is to provide a construction in which panelboard current capacity may be increased without changing the width proportions of the bus bar structure.

A still further object is to provide a construction of this type for an adapter so that a breaker may be used as a general purpose device or as a main breaker for a panelboard.

10 These as well as further objects of this invention shall become readily apparent after reading the following description of the accompanying drawings in which:

FIGURE 1 is a plan view of a panel-board constructed in accordance with the teachings of the instant invention.

FIGURE 23 is a cross-section taken through line 23-23 of FIGURE 21 looking in the direction of arrows 23-23.

FIGURE 24 is a plan view of an extension to be added to an arm of the insulator of FIGURE 6 for constructing a panelboard with additional circuit breaker locations.

FIGURE 25 is a side elevation of the insulator extension of FIGURE 24.

FIGURE 26 is a bottom view of the insulator extension of FIGURE 24.

FIGURE 27 is a cross-section taken through line 27-27 of FIGURE 24 looking in the direction of arrows 27-27.

FIGURE 28 is an end view of the extension of FIGURE 24 looking in the direction of arrows 28-28 of FIGURE 24.

Now referring to the figures. Panelboard 39 of FIGURE 1 includes mounting plate 31 which carries U-shaped insulator 35 (FIGURE 6), add on insulators 53, 54 U-shaped bus bar 36 (FIGURE 9), bus bar 37 (FIGURE 11), U-shaped bus bar 38 (FIGURE 10), terminal extensions 39A, 39B and 39C and wire grip assemblies 40A, 40B and 40C. It is noted that where elements of like constructions are designated by the same reference numeral with different suffixes in plan views, these suffixes have been omitted in side views.

Insulator 35 is a U-shaped member whose web at the forward surface thereof is provided with four barriers 41A, 41B, 41C and 41D which extend parallel to the arms of the U and define recesses for line terminal or wire grip assemblies 40.

Insulator 35 is substantially hollow and having internal U-shaped ribs 42, 43 which are generally parallel to the outer walls 44, 45 of insulator 35 thereby defining three substantially parallel U-shaped slots 46, 47, 48 which are open at the bottom of insulator 35. The inner wall 45 is provided with inwardly extending lugs 49 having notches 50 which receive screws 51 for securement of insulator 35 and the elements mounted thereto to mounting plate 31. Straight insulator sections 53 and 54 are added to the arms of U-shape insulator 35 at lines 93 and 97 to form extensions of the arms. The construction and function of insulators 53, 54 will hereinafter be explained.

As seen in FIGURES 9 and 9A, inner bus bar 36 is a U-shaped member constructed of sheet material bent in the plane of this sheet material. The upper edge of bus bar 36 along the arms thereof is provided with offsets 54A, 55A, 56A and 57A. In addition bus bar 36 is provided with lugs 58A and 59A with the latter being at the web and the former being at one arm. The boundaries between these offsets 54A through 59A are provided with apertures 60 to facilitate bending these offsets to positions at right angles to the main portion of bus bar 36. Offsets 54A through 59A are also provided

with threaded apertures 61 which are adapted to receive screws for making electrical connections to circuit breakers.

Outer bus bar 38, shown in FIGURES 10 and 10A, is of similar sheet construction as bus bar 36. The offsets of bus bar 38 positioned along the arms thereof for engagement by branch circuit breakers, are designated 54C-57C while the offsets for connection to the energizing circuit are designated 58C and 59C. Each of the latter group of offsets is also provided with threaded apertures 61.

The center bus bar 37 illustrated in FIGURES 11 and 11A is constructed of rod-like material with offsets formed by transverse deformed portions. The branch circuit connecting offsets of bus bar 37 are designated 54B-57B while the single offset for line connection is designated 59B. However, this last offset is provided with two threaded apertures 61 while the offsets 54B-57B are each provided with a single threaded aperture 61.

The current carrying capacity of the panelboard is determined by the height "H" of bus bars 36 and 38 since the thickness "T" of these bus bars is maintained uniform regardless of circuit breaker current rating. In order to increase the current carrying capability of the middle phase, U-shape bus bar 37, bus bar 65 constructed of rod-like material, is connected in parallel with center bus bar 37 by bringing it into abutment therewith as shown in FIGURE 2. It has been found advantageous to weld bus bar 65 to bus bar 37, as clearly seen in FIGURE 1, at points designated W as well as at other intermediate points not indicated. The widths of bus bars 36 and 38, as seen in FIGURE 3, are for a maximum capacity panelboard consistent with the construction of insulator 35. Sealing wax 99 is inserted in the slots of insulator 35 below bus bars 38 and 36 to provide an insulating barrier between these bus bars and mounting plate 31. FIGURE 5 shows the height of the inner and outer bus bars for the case where the capacity of the panelboard is approximately half that of FIGURE 3. Under these circumstances the inner and outer bus bars 36a and 38a are approximately half the height of bus bars 36 and 38.

After assembly in the insulators, the offsets of bus bar 36 are outwardly bent, the offsets of bus bar 38 are inwardly bent, and the offsets of bus bar 37 are located forward of the main portion of bus bar 37. As clearly seen in FIGURE 2 the offsets of all three bus bars 36, 37 and 38 are positioned so that the forward surfaces thereof lie in a single plane parallel to the plane of mounting plate 31 and are exposed at the front surface of insulator 35.

The forward surface of insulator 35 is provided with apertures 65A, 66A, 68A and 69A through which offsets 55A, 56A, 58A and 59A, respectively, extend. Insulator apertures 65C, 66C, 68C and 69C are provided for the passage of offsets 55C, 56C, 58C and 59C, respectively. In addition the top surface of insulator 35 is provided with apertures 65B, 66B and 69B through which portions of offsets 55B, 56B and 59B, respectively, extend. Inner bus bar 36 is disposed within insulator slot 46 with the outward bending of the offsets of bus bar 36 providing mechanical securement of bus bar 36 to insulator 35. Similarly outer bus bar 38 disposed within slot 48 is mechanically secured to insulator 35 by inwardly bending the offsets of bus bar 38. The mechanical position of center bus bar 37 is maintained by appropriately shaping the walls of groove 47 and also by providing insulators 72 (FIGURE 2) disposed within groove 47 to space the center bus bar or bus bars as the case may be from base plate 31.

Two screws 73 electrically and mechanically secure strap 39A to offsets 58A and 59A. Similarly two screws 74 electrically and mechanically secure strap 39B to offset 59B while two screws 75 mechanically and electrically secure strap 39C to offsets 58C and 59C. Nut and

bolt securing means fasten connector assemblies 40A-40C to the respective straps 39A-39C. Leg 76, for the mechanical securement and positioning of circuit breakers mounted in panelboard 30, is positioned between the arms of U-shape bus bars 36-38 and extends parallel to these arms.

Each of the insulator sections 53 and 54 are of substantially identical construction the only differences being the locations of mechanical securing lugs 53A and 54A, respectively, and the locations of apertures through which the bus bar offsets extend. Insulator 54 is illustrated in detail in FIGURES 24 through 28. Insulator 54 is provided with internal grooves 46A, 47A and 48A which are aligned with grooves 46, 47 and 48, respectively, of insulator 35 forming extensions thereof. The forward surface of insulator 54 is provided with apertures 67A, 67B and 67C which communicate with grooves 46A, 47A and 48A, respectively, so as to provide passages through which offsets 57A, 57B and 57C, respectively, extend. In a similar manner insulator 53 is provided with internal grooves forming extensions of grooves 46 through 48 of insulator 35 at the end of the other arm of insulator 35. Additional insulators 53, 54 may be added as required to increase the number of circuit breaker mounting locations in a given panelboard and in the event that additional locations are desired it is merely necessary to increase the lengths of the bus bar arms.

The embodiment of FIGURE 14 differs from the embodiment of FIGURE 1 in that the web of insulator 135 is much narrower than the web of insulator 35. This construction is provided so that there will be a removable terminal base 100 which carries assemblies 40A, 40B and 40C. Screws 101, extending through clearance apertures in barriers 102, 103 of removable base 100, mechanically secure removable terminal base 100 to mounting plate 31. Extensions of barriers 102, 103 extend into grooves at the end of barriers 104, 105, respectively, of U-shape insulator 135 at the web thereof and end barriers 106, 107 of base 100 overlap the ends of the web of insulator 135.

By making terminal base 100 removable greater flexibility is provided in the system. Specifically base 100 may be removed and replaced by a main switch or circuit breaker interposed between the panelboard and its energizing source. FIGURE 15 shows three phase circuit breaker 110 connected to insulating base 135 and the current carrying elements associated with base 135. Circuit breaker 110 is of the type disclosed in the aforesaid application Serial No. 285,681, filed June 5, 1963.

In FIGURE 15 base 100 has been replaced by adapter 115 shown in plan view in FIGURE 16. Adapter 115 includes insulator 120 provided with extensions 117 having slots 118 for mechanical securement of adapter 115 to mounting plate 31 by fastening means 119 (FIGURE 15). Insulator 120 is formed as a closed loop provided with concentric closed loop slots open at the rear of insulator 120. Within the slots are disposed bus bars 136, 137 and 138 similar in construction to bus bars 36 through 38, respectively. Bus bars 136 and 138 are each U-shaped members while bus bar 137 is formed as a loop having an opening therein. Bus bar 136 is provided with offsets 139A, 140A and 141A, bus bar 138 is provided with offsets 139C, 140C and 141C, while center bus bar 137 is provided with offsets 139B, 140B and 141B.

Offsets 139A, 139B and 139C are disposed with the threaded apertures 61 thereof in a straight line parallel to one of the long legs of insulator 120. The remaining offsets are positioned so that the threaded apertures 61 thereof are aligned along the other long leg of insulator 120. Insulator 120 is provided with barriers 145, 146 which are received by the notches in the barriers 104, 105, respectively, of insulator 135. Rib 147, for the mechanical securement of circuit breaker 110, is disposed within the cavity formed by insulator 120 and is posi-

tioned parallel to the long legs of insulator 120 remote from the legs having offsets 139A, 139B and 139C. As seen in FIGURES 15 and 18 suitable straps 151, 152 connect the bus bars of adapter 115 to the bus bars mounted to base 135. The line terminals of circuit breaker 110 are electrically connected to offsets 139A, 139B and 139C through offset straps 153. Line connections are made directly to the load terminals of circuit breaker 110.

In the embodiment of FIGURE 20 adapter 115 has been eliminated and connections are made from adapter 153 to strap 151, directly by means of U-shape conductors 159 having insulating coverings 160. As clearly seen in FIGURE 20, the webs of conductors 159 pass beneath circuit breaker 110. In FIGURE 18C circuit breaker 110 is shown mounted to rib 147 for use as a general purpose breaker. In this embodiment the insulation covered U-shaped conductor 159, instead of being connected at their right ends 161 to strap 151, are provided with wire grips 162. Each wire grip 162, as clearly seen in FIGURES 18A and 18B, is provided with clearance apertures 163 for the passage of screws 164 which secure connector 162 to conductor 159. Connector 162 includes clamping screw 165 mated to a threaded aperture positioned between clearance apertures 163 and 25 extending into cavity 166 which is enterable from the side of mounting rib 147 remote from circuit breaker 110.

In the adapter 200 of FIGURES 21 through 23 loop insulator 201 is provided with two rather than three, slots to receive bus bars. One slot is provided for center bus bar 205 which is formed as an open loop while the other slot is provided for bus bars 204 and 206. Thus, it is seen that the insulator 201 may be considerably narrower than insulator 120. Bus bar 204 is of the same construction as bus bar 136 of FIGURE 16 while bus bar 206 is a mirror image of bus bar 204 and takes the place of bus bar 138 of FIGURE 16. Insulator 201 is provided with an enlarged notch 210 at the bottom thereof to provide ventilation for circuit breaker 110.

Thus, this invention provides a novel construction for a multiphase panelboard. This construction specifically provides points for electrical connections which are equally spaced by a distance which permits either single pole or multipole circuit breakers of a particular construction to be inserted indiscriminately at any position on either of two legs of the panelboard. This specific circuit breaker construction is one in which mechanical securement of the circuit breaker is of a rib disposed between the portions of the panelboard conductors to which the branch circuit breakers make electrical connection.

Although there has been described a preferred embodiment of this novel invention, many variations and modifications will now be apparent to those skilled in the art. Therefore, this invention is to be limited, not by the specific disclosure herein, but only by the appending claims.

The embodiments of the invention in which an exclusive privilege or property is claimed are defined as follows:

1. A device of the class described comprising a mounting member having a plate-like portion, a plurality of bus bars, means mounting said bus bars in insulating relationship to said mounting member forward of plate-like portion, a first and a second of said bus bars each having a main portion and a plurality of offsets defining locations for making electrical connections to the respective bus bars, said offsets of said first and said second bus bars having the surfaces thereof remote from said plate-like portion positioned in a plane parallel to said plate-like portion, said offsets of said first bus bar projecting in a first direction from the main portion of said first bus bar, said offsets of said second bus bar projecting in a second direction from said main portion of said second bus bar, said first direction being different than said second direction, a third of said plurality of said bus bars positioned between said first and said second bus bars, said third bus bar having a main portion and a plurality of offsets defin-

ing locations for making electrical connections thereto, said offsets of said third bus bar having the surfaces thereof remote from said plate-like portion positioned in said plane, said first, said second, and said third bus bars each formed as separate concentric loops, a first, a second and a third U-shaped bus bar insulatingly mounted from one another and from said mounting member, each of said U-shaped bus bars having offsets defining locations for making electrical connections to said bus bars, said offsets of said U-shaped bus bars being positioned with the surfaces thereof remote from said plate-like portion in a plane parallel thereto, and means electrically connecting said first, said second, and said third loops to said first, said second, and said third bus bars, respectively, at the webs thereof.

2. The device of claim 1 in which there is a first circuit breaker mounting rib disposed midway between the arms of the U-shaped bus bars, extending parallel to these arms, a second circuit breaker mounting rib secured to said plate-like portion and operatively positioned within the loops.

3. A panelboard comprising:

a mounting member having a plate-like portion, a plurality of bus bars; means mounting said bus bars in insulating relationship to said mounting member forward of said plate-like portion; a first and a second of said bus bars each having a U-shaped main portion and a plurality of offsets defining locations for making electrical connections to the respective bus bars, a third of said plurality of bus bars positioned between said first and said second bus bars, said third bus bar having a U-shaped main portion and a plurality of offsets defining locations for making electrical connections thereto, said offsets of said third bus bar projecting forward of said main portion of said third bus bar, said offsets of said first, second, and third bus bars having the surfaces thereof remote from said plate-like portion positioned in a plane parallel to said plate-like portion, said offsets of said first bus bar projecting in a first direction from the main portion of said first bus bar and in front of said third bus bar, said offsets of said second bus bars projecting in an opposite direction from said main portion of said second bus bar and in front of said third bus bar, said first and said second bus bar main portions being constructed of material having a cross-section in which the major dimension is many times greater than the minor dimension, the minor dimension of the third bus bar cross-section being greater than said minor dimensions of said first and said second bus bars, a circuit breaker mounting rib positioned midway between the arms of the U-shaped bus bars and extending parallel thereto; a first group of said offsets arranged in a first line and a second group of said offsets arranged in a second line, said first and said second lines being parallel to said rib and equally spaced therefrom.

4. The device of claim 3 in which the offsets in each of said lines are positioned in a phased sequence arrangement.

5. The device of claim 3 in which there is a terminal means connected to the bus bars at the web of the U.

6. A panelboard comprising a mounting member having a plate-like portion, a plurality of U-shaped bus bars, U-shaped means mounting said bus bars in insulating relationship to said mounting member forward of said plate-like portion, said U-shaped means comprising a web portion and two extending arm portions, a first and second of said bus bars each having a main portion and a plurality of offset connecting members defining locations for making electrical connections to said respective bus bars, said offset connecting members of said first and second bus bars having portions thereof remote from said plate-like portion and positioned in a plane parallel to said plate-like portion; said portions of said offset connecting

members of said first bus bar projecting in a first direction from the main portion of one arm of said first U-shaped bus bar, said portions of said offset connecting members of said second bus bar projecting in a second direction from said main portions of the other arm of said second U-shaped bus bar, said first direction being different than said second direction, a third U-shaped bus bar having a main portion and a plurality of offset connecting members defining locations for making electrical connections thereto, said offset connecting members of said third bus bar having a portion thereof remote from said plate-like portion and positioned in said plane, said portions being capable of being electrically connected to circuit breakers mounted between the extending arm portions of said U-shaped means.

7. The panelboard of claim 6 in which said portions of the offset connecting members of said first, second, and said third bus bars are intended to be engaged by circuit breaker terminals and are positioned in a phased sequence arrangement.

8. The panelboard of claim 6 in which there is a circuit breaker mounting rib positioned midway between the arms of the U-shaped bus bars and extending parallel thereto.

9. The panelboard of claim 8 in which a first group of said portions of said offset connecting members are arranged in a first line and a second group of said portions of the offset connecting members are arranged in a second line, said first and said second lines being parallel to said rib and equally spaced therefrom.

10. A panelboard comprising a mounting member having a plate-like portion, a plurality of bus bars, means including a looped insulator mounting said bus bars in insulating relationship to said mounting member forward of said plate-like portion, a first and a second of said bus bars each having a main portion and a plurality of offsets defining locations for making electrical connections to the respective bus bars, said offsets of said first and said second bus bars having the surfaces thereof remote from said plate-like portion positioned in a plane parallel to said plate-like portion, said offsets of said first bus bars projecting in a first direction from the main portion of said first bus bar, said offsets of said second bus bar projecting in a second direction from the main portion of said second bus bar, a third of said plurality of bus bars being formed as a loop, said loop being substantially rectangular, said third bus bar having a main portion and a plurality of offsets defining locations for making electrical connections thereto, said offsets of said third bus bar having the surfaces thereof remote from said plate-like portion and positioned in said plane, a circuit breaker mounting rib secured to said plate-like portion and being operably positioned within the loop of the insulator, a first group of said offsets being arranged in a first line and a second group of said offsets being arranged in a second line, said first and said second lines being parallel to said rib.

11. The device of claim 10 in which said first and said second bus bar main portions are constructed of material having a cross-section in which the major dimension is many times greater than the minor dimension, the minor dimension of the third bus bar cross-section being greater than the minor dimensions of said first and said second bus bars.
